[57] CLAIM

I claim the ornamental design for a corn holder, as shown and described.

DESCRIPTION

FIG. 1 is a front view of a corn holder showing my new design with a portion shown in dotted lines for environmental purposes only and not part of the claimed design;

FIG. 2 is a top plan view thereof;

FIG. 3 is a right side view thereof;

FIG. 4 is a back view thereof;

FIG. 5 is a left side view thereof; and,

FIG. 6 is a bottom plan view thereof.
